CLAIM

The ornamental design for a fluid height restriction device, as shown and described.

DESCRIPTION

FIG. 1 is a front perspective view of a fluid height restriction device in accordance with the invention;
FIG. 2 is a front view of FIG. 1;
FIG. 3 is a back view of FIG. 1;
FIG. 4 is a left side view of FIG. 1;
FIG. 5 is a right side view of FIG. 1;
FIG. 6 is a top view of FIG. 1; and,
FIG. 7 is a bottom view of FIG. 1.
